TIMER FOR A GAME

Armand Godefroid, Berlin-Schöneberg, Germany

Application June 16, 1933, Serial No. 676,199
In Germany June 18, 1932

3 Claims. (Cl. 161—17)

This invention relates to games, and more particularly to games in which a play-body is moved towards a mark in a manner to require a certain skillfulness or ability on the part of the player.

5 This invention is an improvement over my co-pending application 676,198 filed June 16, 1933.

Known games of this kind in which a play-body is moved towards a mark have heretofore been connected with the great disadvantage that 10 they do not comply with the present-day ideas and requirements regarding registration and measurement of the time required by the player in order to move the play-body from the start to its final position.

15 An exact registration of different play results and a proper timing of the latter is now-a-days generally in use not only with pugilistic combats and riding-tournaments, but also with all other exercises having sporting character. In games 20 using a ball or other play-body registering and time-measuring devices have heretofore never been used. In accordance with the present-day requirements, therefore, an exact measuring of the time within which all play-results are attained are an important requisite, if the game 25 shall be serious and permanently entertaining.

The drawback connected with known games is avoided according to the present invention by providing a stop-watch permitting an exact indication of the time during which the play-body 30 has moved on its way from the start to its final position. By means of such a registration of time all errors, quarrels or disputes which may arise when playing with games of the ordinary kind 35 will be positively avoided, the use of an exactly working mechanical means of the nature of a time-piece rendering it possible to indicate and register even the slightest differences between play-results which appear to be alike if games 40 of the ordinary kind are used. As the performance of said mechanical means is effected in the new game during the rolling motion of the play-body either by action of its starting force or by action of its weight or both, there is 45 attained an automatic and consequently absolutely reliable indication of the play-results.

In accordance with the nature of the present invention provisions are made to insure regular performance of the play. This is accomplished 50 according to the invention by causing the several parts of the registering device to operate in positive dependence from one another, in such a manner that said device will control the proper sequence of the individual functions and positively maintain this sequence during the course

of the play. With the present game a new play can only be commenced with, if the stop-watch had previously been set into zero position, whereby the starting lever is again released permitting a single actuation thereof. During the course 5 of the play the starting lever remains locked and the stop-watch can only be set into zero position subsequent to being stopped, the stopping being effected by the play-body when arriving in its final position. The play-result is thus indicated 10 and kept fixed until a new play is commenced with, the indication being covered up by a glass-pane. It may be noted that the play-body permanently remains within the game.

By constructing the game in the aforementioned manner all errors will be avoided and, in addition, any attempts of deception on the part of a player are positively rendered impossible.

This invention is explained herein as applied to a game consisting of a play-field, a play-body 20 freely movable on said field, and a freely movable pushing or guiding device for said play-body. The invention, however, may also be used in connection with games other than that described herein and shown in the drawings. 25

In the drawings,

Fig. 1 is a perspective view of one form of construction of the game,

Fig. 2 a vertical longitudinal section on the line II—II, Fig. 3,

Fig. 3 a plan-view on Fig. 2 with the cover of the game removed, said cover forming the play-field of the game,

Fig. 4 an enlarged vertical cross-section on the line IV—IV, Fig. 3,

Fig. 5 a section taken along the broken line V—V—V, Fig. 4,

Fig. 5a a partial vertical section on the line Va—Va—Va, Fig. 4,

Fig. 5b a partial plan view on Fig. 5a, 40

Fig. 6 a vertical cross section through another form of construction of the game,

Fig. 7 a section on the line VII—VII, Fig. 6,

Fig. 8 a perspective view of a detail forming part of Fig. 7, 45

Figs. 9 and 10 are sections similar to that shown in Fig. 7 in a different position of the parts of the game,

Fig. 11 is a partial section similar to the section shown in Fig. 6 in another different position of the parts, 50

Fig. 12 a section similar to that of Fig. 11 in a still other position of the parts, and

Fig. 13 a vertical section on the line XIII—XIII, Fig. 12. 55

- According to Figs. 1, 2 and 3 the game consists of a casing 1 having a cover constituting a play-field composed of individual fields 2, 3, 4, 5 and 6. Intermediate said individual fields are provided 5 slots 7 which are partly covered up by tongues 8. The start for the ball or play-body 10 is indicated at 9. The mark or goal is of the form of a pocket 11 provided with an aperture 11' through which the play-body may fall.
- 10 Underneath the play-field are arranged a series of catching devices 37 for reception of the play-body which falls either through the aperture 11' or through the slots 7. A running groove 38 is joined to each of said catching devices 37.
- 15 A flap 39 is hinged to the under end of all the parallel grooves 38 as shown in Figs. 2 and 5 upon an axis 40, a lever 41 or the like is fixed to said axis around a horizontal axis 40. The lever 41 has a lateral cam 41'' (Fig. 5a and 5b) which 20 acts on a button 41' of a stop-watch 42, thus stopping the latter as soon as said flap 39 is rotated around said axis 40 by action of the weight of a ball or play-body 10 when rolling onto said flap. The length of the flap 39 is so dimensioned 25 that the play-body 10 will come to rest between the free front end of said flap and a window 43 permitting to see into which groove the play-body has rolled. This position of the flap 39 and of the play-body is indicated in Fig. 5 in dotted lines.
- 30 The flap 39 is balanced by means of an adjustable counterpoise 44.
- Underneath the free front end of the flap 39 there is an inclined connecting track 46 leading towards a gutter 45. The groove 45 ends in front 35 of a conveying device which in the example of construction shown is of the form of rotatable drum 47 equipped with pockets 48 serving for the reception of the play-body 10, said pockets being open at that side at which the play-body runs in 40 (Figs. 4 and 5). A fixed wall 49 arranged beside the drum 47 closes up said pockets 48. The wall 49, however, is provided at its upper portion with an outlet 50 and at its under portion with an inlet 51 for the play-bodies. The outlet 50 is 45 positioned in front of the end of an inclined gutter 52 leading towards the start 9.
- The drum 47 is mounted upon a shaft 53 and 50 may be rotated by means of a ratchet-wheel 54 and a feeding pawl 56 mounted at the end of a displaceable pin 57 provided with a pressure button. A fixed resilient locking pawl 59 is in engagement with a locking wheel 55 mounted on the shaft 53 to prevent backward rotation of said shaft.
- 55 The shaft 53 of the drum 47 extends as far as to the stop-watch 42 and is provided at its extended end with a ratchet-wheel 53' (Figs. 4, 5a and 5b). During each feeding motion of the drum by a distance between two pockets 48 the wheel 53' by the lever 41 disengages the stop-watch 42 so that the latter is set in motion, at the same time moving the flap 39 back into the position shown in full lines in Fig. 5.
- A pressure button 59', which serves in the usual 60 manner for resetting the stop watch 42 to zero, is arranged on the stop watch; the casing 1 of the game has an opening 59'' through which the button 59' is accessible.
- The mode of operation is as follows: Before 65 commencing the play one half of the pockets 48 on the drum 47 is filled with play bodies, for instance with play-balls 10, and the stop-watch 42 set to zero. The first player now presses the button on the pin 57, thus rotating the drum 47 a distance between two pockets.

During rotation of the drum a play-ball 10 comes in front of the outlet 50 in the wall 49. By reason of the inclination of the bottom of the chamber shown in Fig. 4, the play-ball will run into the gutter 52 and arrive at the start 9 of the play-field.

Upon rotation of the drum the shaft 53 thereof has actuated the lever 41 to release the stop-watch 42 by means of the ratchet wheel 53', the lever 41 and the cam 41'', so that the watch will start running. Simultaneously therewith the flap 39 fixed upon the axis 40 is swung upward so that the ball 10 resting on the free end of said flap as shown in Fig. 5 may move along the gutter 45 through the aperture 51 in the wall 49 15 and arrive at a free pocket 48 in the drum 47.

Immediately upon arrival of the ball 10 at the start 9 the player moves said ball 10 on the play-field upward in direction towards the mark with the aid of a pushing or guiding device (not 20 shown).

If the player succeeds in pushing the ball forward as far as to the goal 11, said ball will fall through the aperture 11' provided underneath said goal onto the rearmost catching surface 37 25 and roll off the latter in the groove 38 appertaining thereto in forward direction as far as onto the flap 39. The respective groove has the ordinal number 5 as shown in Fig. 1. The ball now by action of its weight depresses the flap 39 and 30 runs onto the inclined surface 46. In this position the ball is kept fixed by the depressed flap 39 as indicated in Fig. 5 in dotted lines. If the flap 39 moves downward, the shaft 40 is rotated thereby stopping the stop-watch 42 by means of 35 the lever 41 and the cam 41''. The watch now exactly indicates the time which had been necessary for the ball to run from the drum 47 to the start 9, to be brought from the start as far as to the goal and to run down to the flap 39. As the 40 time for the movement of the ball from the drum to the start and from the goal to the flap is always the same the indications of the stop watch show exactly the difference between the times necessary for the diverse players to carry the 45 ball from the start to the goal.

If the ball should fall through slot 7 of the first row of slots, figured from the start 9, Fig. 1, the ball runs into a groove 38 designated by the 50 ordinal number 1.

In case the ball does not arrive at the goal 11 and falls through a slot 7, the stop-watch 42 likewise indicates the sum of the time that had been needed by the player to carry the ball as far as to the respective slot 7 and of the constant time 55 necessary for the movement of the ball from the drum 47 to the start 9 and from the slot 7 to the flap 39. After having ascertained the time and the number of the groove into which the ball has run, the stop-watch is set to zero by pressing the 60 button 59', Fig. 1.

The ball kept by the flap 39 is released as soon as upon subsequently depressing the button on the pin 57 the shaft 53 is rotated and as soon as rotation is imparted to the shaft 40 by the shaft 65 53. The shaft 53 acts by means of the wheel 53' on the lever 41 and thus rotates the shaft 40 so that the flap 39 is released and passes into the position indicated by full lines in Fig. 5.

The form of construction of the new game as 70 shown in Figs. 6, 7, 8, 9, 10, 11, 12 and 13 also comprises the groove 38'' which is present in the above described form of construction of the game as well as the flap 39'' with the adjustable counterpoise 44'', the shaft 40'', the stop-watch 75

42", the window 43", and the feed-drum 47" on the shaft 53".

The drive for the feed drum 47" in the present case, however, is different from that shown in the above described form of construction of the new game. A lever 67 provided with a pressure-button 65 and a coiled spring 66 engages the upper end of a vertical rod 68 which laterally carries a pin 69. At the under end of the rod 68 is provided a leaf-spring 70, a feeding pawl 71 being laterally associated therewith. Said pawl 71 engages with a ratchet-wheel 72 fast on the shaft 53" of the drum 47". A fixed resilient locking pawl 73 prevents backward rotation of said ratchet-wheel. The under end of the spring 70 is bent off in lateral direction to form a horizontal arm 74 co-operating with an arm 75 on the shaft 40".

The rod 68 carries near its upper end a laterally projecting nose 76 having an oblique under surface and is positioned within a slot 78 in the slide 77.

On the under side of the slide 77 there is a pin 79 engaged by a spring 80 fast on a member 81 which serves, both as a guide for the rod 68 and as a bearing for the shaft 53". The member 81 is equipped with a pawl 82 pressed upward by action of a spring 83.

The slide 77 has a further slot 84 through which extends a vertical rod 85. Fixed to the under end of said rod are two tongues 86 and 87 which, as shown in Fig. 8, are preferably made integral with each other.

Underneath the tongue 86 the shaft 40" carries a segment 88 having a radially directed incision 89. The shaft 40" further carries a preferably resilient arm 90 and co-operates with the balance wheel 91 of the stop-watch 42" as shown in Fig. 6.

Within the range of action of the tongue 87 is a lever 92 formed or carried by the end of a shaft 93. Said shaft carries a gutter 94 parallel to its axis, said gutter 94 corresponding to the groove 45 shown in Figs. 4 and 5. The gutter 94 has a lateral guide surface 95 by which the play-body 10" may be carried from the flap 39" towards the gutter 94. An arm 96 is provided on said guide surface 95, said arm pressing said guide surface upward by action of a spring 97.

The rod 85 carries laterally a nose 98 having an oblique under surface and carrying an arm 99 extending as far as to the stop-watch 42". The rod 85 with the pressure button 100 at its upper end is pressed upward by a spring 101.

The mode of operation is as follows: Fig. 6 shows the game with all of its parts in playing position, that is in that position in which a play-body is pushed by a player onto the play-field of the casing 1". The rods 68 and 85 are locked and the nose 76 is positioned underneath the slide 77 so that the rod is prevented against being raised by the pressure button 65 and the lever 67. Underneath the rod 85 there is positioned a full portion of the segment 88 as shown in Fig. 7.

If upon completion of a play the ball 10" presses the flap 39", the shaft 40" with the segment 88 is rotated so that the slot 89 will come into position underneath the tongue 86. By this the rod 85 is unlocked as shown in Fig. 9.

If the button 100 is depressed after having as-

certained the ordinal number of the groove 38 at which the play-body has arrived, as shown in Fig. 1, and after having ascertained the duration of the play, the game is again put into condition ready for playing. The parts will thus come into the position shown in Figs. 10 and 11. The tongue 87 now depresses the lever 92 so that the shaft 93 is rotated. The groove 94 and the connecting track 95 are now tilted so that the ball 10" will no more be engaged by the flap 39", this condition being shown by the dash-dotted connecting track 95 in Fig. 9.

The lateral arm 99 on the rod 85 acting on the stop-watch will set the latter into zero-position. The slide 77 is moved towards the right by the nose 98 on the rod 85 and locked in this position by the pawl 82 as shown in Fig. 11. Upon releasing the pressure button 100 the rod 85 will again move upward.

If a new play is commenced the button 65 is depressed causing the rod 68 to be raised so that the nose 76 thereon will enter the slot 78 in the slide 77. The pin 69 now releases the pawl 82 as shown in Fig. 12 and the slide 77 may now be moved towards the left by the spring 80. At the end of this motion the slide is engaged by the nose 76 on the rod 68.

The feeding pawl 71 with the spring 70 rotates the ratchet-wheel 72 on the drum-shaft 53" a distance between two teeth. In consequence thereof a play-body falls out of the drum and now runs along the gutter 52" towards the start 9". The arm 74 of the spring 70 acts upon the lever 75, thereby rotating the shaft 40" with the result that the flap 39" is again raised to assume the position represented in full lines in Fig. 13. The lever 92 now releases the balance-wheel of the stop-watch 42" so that the latter is set again into operation. The parts now again assume the position shown in Figs. 6 and 7 which position is maintained until after completion of the play the ball which has fallen through the aperture 11' of the goal 11 or through one of the slots 1" runs onto the flap 39" and rotates the shaft 40".

I claim:

1. A timer for a game containing a play field with apertures, a play body to be pushed forward by a player and catching devices for said play body, said timer comprising a stop watch and a drum for said play body, a device adapted to release said stop watch and simultaneously said play body, a plurality of outlet grooves joined to said catching devices for the play body, a swingably mounted flap at the ends of said outlet grooves, an axis, said flap fixed upon said axis and adapted to be swung by the play body, a member fixed upon said axis, said member adapted to stop said stop watch.

2. A timer as claimed in claim 1, including a tiltable connecting track for the play-body under said flap, a pushing rod for said track, and a locking device for said pushing rod, said locking device being connected with said flap.

3. A timer as claimed in claim 1, including means for setting said stop-watch into zero position.

ARMAND GODEFROID.
